BADGE

Filed April 19, 1929

C. L. Stange, INVENTOR
BY *Victor J. Evans*
ATTORNEY

UNITED STATES PATENT OFFICE

CHARLES L. STANGE, OF ST. LOUIS, MISSOURI

DESIGN FOR A BADGE

Application filed April 19, 1929. Serial No. 30,935. Term of patent 14 years.

To all whom it may concern:

Be it known that I, CHARLES L. STANGE, a citizen of the United States of America, residing at the city of St. Louis, in the State of Missouri, have invented a new, original, and ornamental Design for a Badge, of which the following is a specification, reference being had to the accompanying drawings, forming a part thereof.

The figure is a perspective view of a badge showing my new design.

The crown is the important feature of the design, the upper and lower edges thereof be-

ing curved upwardly in parallelism, with rounded projections representing jewels or the like arranged in row and arcuate formation adjacent the lower edge, and integrally connected with the crown is a star having a portion extending above the upper edge thereof, and forming a portion of said upper edge which is of substantially zigzag formation.

I claim:

The ornamental design for a badge as shown and described.

CHARLES L. STANGE.
